UNITED STATES PATENT OFFICE.

BURNHAM C. STICKNEY, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,416,520.

Specification of Letters Patent. Patented May 16, 1922.

Application filed November 8, 1918. Serial No. 261,589.

To all whom it may concern:

Be it known that I, BURNHAM C. STICKNEY, a citizen of the United States, residing in Elizabeth, in the county of Union and State of New Jersey, have invented certain new and useful Improvements in Combined Typewriting and Computing Machines, of which the following is a specification.

This invention relates generally to combined adding and typewriting machines, and is of special value in those machines in which indexing pins or devices are set up at the operation of the numeral keys and the numbers, so indexed are subsequently carried into a totalizer or register; an example of this class of machine being the well-known Underwood bookkeeping machine which is illustrated in the patent to Minton, 1,280,065, and other patents.

The indexing pins are usually arranged nine in a row, each row representing a different denomination. Independently operable pin-setting bars are arranged transversely above the index pins, one bar connected to each numeral key, so that any key can set a pin in any row. All of these pins are normally out of range of these setting bars; but through suitable mechanism the typewriter carriage operates to project the pin rows one at a time into the paths of the setting bars. Hence, the selection of an indexing pin depends partly upon the position of the typewriter carriage, and partly upon the selection of the key. Springs return the setting bars and the pin bars after the pin-setting operation. When all of the pins have been set up for a number, a general operator is usually employed to advance all of the dial wheels simultaneously, each to an extent determined by the described setting of the pin in its associated row.

In practice, it is important to guard against erroneous setting of the index pins, since errors of this kind are difficult, if not impossible, to detect. One source of possible error is found in the liability of the obstruction of the movement of one or two of the bars which carry the rows of index pins. The return of the bar upon which a pin has just been set may be delayed, or the advance of the bar of next lower denomination, which at the moment is being advanced by means of the train of mechanism which connects

it to the typewriter carriage, may be hindered. In either case an error is liable to occur, since all of the pins must be in their intended places at the operation of the setting bar, as otherwise a wrong pin may be set.

The return of the pin-carrying bar, after the pin-setting operation, is liable to be slow, owing partly to the weakness of the returning-spring usually employed, and partly to clogging of the bar, or of the parts that must return with the bar. The bar-returning spring is not usually of great tension, because it must be overcome by the power of the typewriter carriage in moving from one step to the next, and it is not desirable to retard the action of the carriage. Hence, in rapid key operation, this sluggishness of return of the pin-carrying bar will sometimes result in the next operated numeral key setting a pin upon the first bar before it can reach normal position; this resulting in faulty action, which it is difficult, if not impossible, to detect, so that an unnoticed error creeps into the computation.

To overcome this difficulty, there is provided a device which, at the down stroke of the numeral key, forces back to normal position any pin-carrying bar that may have been displaced. This is preferably done before the pin-setting bar descends far enough to engage an index pin, and hence there is avoided the liability of false setting of a pin upon the returning pin bar. This clearing device for the pin-carrying bars may be in the form of a transverse bar which is movable downwardly to engage projections on the bars, to cam the bars back. At the same time, this clearing or justifying device may operate to cam forward the pin-carrying bar which is just being advanced, so as to insure that the selected pin thereon may be properly engaged by the descending setting bar.

Said clearing bar is preferably operable by any of the pin-setting bars or linkages. For this purpose, said pin-setting bars may operate a special universal bar, which may be mechanically connected to the clearing bar.

Said special universal bar may be employed for operating the carriage-feeding mechanism of the typewriter, to the end that

said carriage-feeding mechanism, upon its return stroke, may act through said special universal bar to return promptly to normal position the actuated pin-setting bar; and 5 hence at the operation of the key, an all-around clearance is secured; the setting bar being lifted clear of the advancing and retiring pin-carrying bars, and the latter being placed properly with reference to the 10 pin-setting bars.

It should be explained at this point that the numeral keys referred to operate type-bars to print the numbers upon the work-sheet, and that the letter-feeding movement 15 of the typewriter carriage is controlled by the numeral keys, as well as by the alphabet keys of the typewriter. In the Underwood machine, all of the type-bars are provided with heels which operate a curved universal 20 bar, which controls the feeding dogs that operate with the escapement wheel of the carriage; but preferably the heels of the numeral type-bars "1" to "9" are omitted, so that said type-bars cannot operate the universal bar, and hence cannot feed the carriage. The typewriter universal bar cannot return to normal position without simultaneously restoring the special universal bar to normal position, together with the pin- 30 setting linkage which has just been actuated by its type-key.

The adding mechanism is silenced by effecting a disconnection between the typewriter carriage and the denomination trains 35 which advance or displace one by one the rows of index pins, so that all of the index pins remain stationary out of range of any of the pin-setting bars, the special universal bar and the clearing bar vibrating idly 40 at the numeral key strokes. Certain features disclosed herein are disclosed in my pending application No. 260,626, filed November 1, 1918.

Other features and advantages will here- 45 inafter appear.

In the accompanying drawings,

Figure 1 is a sectional side elevation from front to rear of a combined typewriting and computing machine of the Underwood-Han- 50 son type, showing the present improvements in one form. The parts are in normal positions.

Figure 2 shows some of the parts seen at Figure 1, with one of the numeral keys de- 55 pressed to cause its type to print, and also to set an index pin.

Figure 3 is a perspective rear view to illustrate the operative connections between a numeral type-key and the typewriter uni- 60 versal-bar mechanism, also the clearing mechanism for the bars which carry the index pins.

Figure 4 is an enlarged fragmentary per- 65 spective of the clearing bar and the rear end of an index-pin bar.

Figure 5 is an enlarged sectional frag- 70 mentary side elevation showing the clearing bar at the end of its down stroke.

The typewriting mechanism usually com- 75 prises numeral keys 10, alphabet keys 11, key-levers 12, sub-levers 13, and type-bars 14, which swing up against a platen 15 which is mounted upon a carriage 16. The 80 alphabet type-bars have heels 17 to operate a universal bar or frame 18, which is usually 85 carried at its rear portion upon rock-arms 19, and has means 20 to engage a dog-rocker 21, comprising a pair of dogs 22, 23, which move into and out of engagement with the teeth 24 of the escapement wheel 25, the latter connected by a pinion 26 and rack 27 to the typewriter carriage 16. The dog-rocker is provided with a returning spring 28, and the universal bar is also provided with a returning spring 29. The numeral 90 type-bars 14^a, with the exception of the "0" type-bar, are illustrated as having no means to operate the universal bar 18, the heels 17 being cut away from these bars.

The adding or computing mechanism com- 95 prises stems 30 pendent from the numeral keys "1" to "9", in position to descend and engage at their lower ends rock-arms 31 mounted upon the forward ends of shafts 32, which extend forwardly and rearwardly, 100 said shafts carrying a set of driving arms 33 which operate pin-setting linkages, of which there are nine, one for each numeral or digit key. These linkages comprise upper sets of transverse horizontal bars 34, 105 having pins 35 which are engaged by said driving arms 33, and also comprise lower sets of horizontal transverse arms or bars 36, which are the pin-setting bars above referred to. These bars 34, 36 are connected 110 by bell-cranks 37, 38 at their left-hand and right-hand ends, to form parallel motions or linkages. Whenever a key is depressed, the linkage is moved thereby in a direction to depress the bottom bar 36, whose function 115 is to engage the corresponding index pin 39 in any of the rows into which the set of index pins is divided. Each row of index pins is carried upon a separate bar 40, which extends forwardly and rearwardly of the 120 machine, there being nine pins upon each bar, one for each digit. The pins in each row are separated sufficiently to permit the pin-setting or indexing bar to pass down idly between the pins. If, however, one of 125 the pin-carrying bars 40 is previously set forward, the descending pin-setting bar 36 will engage and depress the pin 39 which is in its path, as set forth in said Patent 1,280,065.

The setting forward or displacing of the pin-carrying bars 40, one by one, is effected by means of a dog 41, which is mounted upon the typewriter carriage 16 in a position to traverse a set of jacks 42, which are 130

engaged one after another by said dog. Each jack is vibrated by the dog, and thereby sets forward the associated pin-bar 40, to which it is usually connected by means of a link 43, a lever 44, a transposition device 45 and a bell-crank 46.

It has been the practice to restore the numeral keys to normal positions by means of springs 47, and the pin bars 40 by means of 10 springs 48, these springs being in practice of relatively light tension. There is provided a returning device for the pin setting linkages, consisting of a universal bar 49 extending fore and aft of the machine, and 15 operable by any of the pin-setting bars 36. This bar 49 is used in connection with the usual pin-setting-linkage returning springs (not shown). Said universal bar 49 may be conveniently carried upon arms 50, which 20 are mounted on a shaft 51, thereby forming a bail or rocking frame; and an arm 52 may extend from said frame in position to drive upwardly a thrust-link 53, which, at its upper end, is pivotally connected to a lever 54 25 which is usually found in the typewriting machine, and has a driving connection by means of an arm 55 with the rock-arm or frame 19 which carries the typewriter universal bar, so that at the operation of any 30 numeral key, said typewriter universal bar or frame is given its customary backward movement. A spring 50^a tends to hold universal bar 49 in raised position.

At the release of the numeral key, the 35 typewriter universal bar or frame 18 reacts upon the special universal bar frame 49, and thereby upon the pin-setting bar 36 which at the moment is in engagement with said special universal bar. Through these various instrumentalities, the pin-setting bar 40 may be restored promptly and with certainty, and hence proper clearance between said bar and the index pins 39 is assured, so that there will be no interference either with 45 the return of one pin-carrying bar 40 to normal position, or with the advance of the succeeding pin-carrying bar to setting position.

The arm 52 and the link 53 may be omitted if desired, in employing certain features 50 of the invention, and in that case the heels 17 may be restored to the numeral type-bars.

From an arm of the special universal bar frame extends an elbow 55, which is connected by a link 56 to one of the arms of a bail 57, the cross-bar 58 whereof is employed as 55 a clearance-bar for justifying the pin-carrying bars 40. This clearance-bar comprises preferably a set of beveled teeth 59, one for each of the pin-carrying bars. Each of the 60 latter may have a lateral projection 60, which may be beveled on its forward side at 61, to operate as a cam, whereby when engaged by a tooth of the clearing bar, it will be cammed back to normal position; the 65 clearing bar teeth normally vibrating up and

down just in front of the row of projections 60. Each tooth of the clearing bar is preferably also beveled at 62 upon its front side, to engage the rear side of its associated projection 60 when the latter is being advanced 70 by the carriage through the described train of connections. The clearance-bar 58 may thus operate to complete the movement of the advancing tooth-carrying bar promptly, so that it will present the selected pin in 75 proper position to the descending setting-bar 36. It will be evident that the clearance-bar will also serve to lock the selected tooth-carrying bar in advanced position and the others in their normal positions. 80

When it is desired to silence the adding mechanism, the usual non-add key 63 may be pressed rearwardly, its rod 64 operating a lever or arm 65, which is usually pivoted to the machine, and is provided with a short 85 arm 66 which engages a cam 67 to depress a cam-roll 68 which usually serves the purpose of elevating or holding up to its working position the denomination-selecting dog 41. Hence, when said non-add key is pushed 90 in, these dogs 41 are silenced, and hence none of the pin-carrying bars 40 is displaced, and the operations of the pin-setting linkages are idle. However, the pin-setting linkages all operate the special universal bar 49, and 95 thereby the typewriter universal bar 18, so that typewriting proceeds the same as if the numeral type-bars had heels 17 to operate the universal bar 18. The movement of the clearance-bar will be idle. 100

Variations may be resorted to within the scope of the invention, and portions of the improvements may be used without others.

Having thus described my invention, I claim:

1. In a combined typewriting and computing machine, the combination of numeral keys, a carriage, rows of index pins or devices, means to enable the carriage to displace the index pins row by row, springs for returning the rows of index pins, key-operated index-pin-setting bars, and means operated by the keys for setting the rows of pins back to normal positions. 110

2. In a combined typewriting and computing machine, the combination of numeral keys, a carriage, rows of index pins or devices, bars upon which said rows of pins are carried, springs for returning said bars, projections upon said bars, key-operated index 120 pin setters, and a clearance bar for engaging said projections to aid the springs in returning the bars to normal positions after pin-setting thereon.

3. In a combined typewriting and computing machine, the combination of numeral keys, a carriage, rows of index pins or devices, bars upon which said rows of pins are carried, springs for returning said bars, projections upon said bars, key-operated index 125 pin setters, and a clearance bar for engaging said projections to aid the springs in returning the bars to normal positions after pin-setting thereon. 130

- pin setters, and key-controlled means to locate said bars in normal positions.
4. In a combined typewriting and computing machine, the combination of numeral keys, a carriage, rows of index pins or devices, bars upon which said rows of pins are carried, springs for returning said bars, projections upon said bars, key-operated index pin setters, and key-controlled means to locate said bars either in normal positions on in pin-setting positions.
5. In a combined typewriting and computing machine, the combination of numeral keys, a carriage, rows of index pins or devices, bars upon which said rows of pins are carried, springs for returning said bars, projections upon said bars, key-operated index pin setters, and means for returning any row to normal position in advance of the engagement by any setting bar of another pin.
6. In a combined typewriting and computing machine, the combination of numeral keys, a carriage, rows of index pins or devices, means to enable the carriage to displace the index pins row by row, key-operated index-pin-setting bars, and a clearing-bar operable by said keys and co-operating with means individual to said rows, for returning them to normal positions.
7. In a combined typewriting and computing machine, the combination of numeral keys, a carriage, rows of index-pins or devices, bars upon which said rows are carried, said bars displaceable by said carriage, key-operated devices for setting said pins, projections upon said bars, and a clearance bar or device for engaging said projections, said projections beveled to enable said clearance bar to cam them back to normal positions.
8. In a combined typewriting and computing machine, the combination of numeral keys, a carriage, rows of index pins or devices, bars upon which said rows are carried, said bars displaceable by said carriage, key-operated devices for setting said pins, projections upon said bars, and a clearance bar or device for engaging said projections, said projections beveled to enable said clearance bar to cam them back to normal positions, and said clearance bar also beveled upon its forward side to cam said bars forward to pin-setting positions.
9. In a combined typewriting and computing machine, the combination of numeral keys, a carriage, rows of indexing-pins or devices, bars upon which said rows are carried, said bars displaceable by said carriage, key-operated bars or devices for setting said pins, a universal bar actuated by said setting bars or devices, and means operable by said universal bar in advance of the engagement of a pin by the active setting-bar, for returning to normal position the previously displaced pin-carrying bar.
10. In a combined typewriting and computing machine, the combination of numeral keys, a carriage, rows of indexing-pins or devices, bars upon which said rows are carried, said bars displaceable by said carriage, key-operated bars or devices for setting said pins, a universal bar actuated by said setting bars or devices, and means operable by said universal bar in advance of the engagement of a pin by the active setting-bar, for returning to normal position the previously displaced pin-carrying bar, and simultaneously completing the advance of the active pin-setting bar to indexing position.
11. In a combined typewriting and computing machine comprising a typewriter carriage, a feeding mechanism therefor, a universal bar mechanism to control said feeding mechanism, alphabet type-actions having means connected to operate said universal bar mechanism, numeral type actions unprovided with means to operate said universal bar mechanism, a computing mechanism comprising rows of index pins or devices, denomination-selecting mechanism controlled by said carriage for displacing the index pins or devices row after row, devices individual to said numeral type-actions for setting the index pins or devices on the displaced rows, a special bar universally operable by said setting devices, a connection from said special universal bar to the typewriter universal bar mechanism to operate the latter, and means also controlled by said special universal bar for returning the rows of index pins to normal positions.
12. In a combined typewriting and computing machine comprising a typewriter carriage, a feeding mechanism therefor, numeral type-actions, a computing mechanism comprising rows of index pins or devices, bars carrying said index pins, denomination-selecting mechanism controlled by said carriage for displacing the index pin bars one by one, devices individual to said numeral type-actions for setting the index pins or devices on the displaced rows, a special bar universally operable by said setting devices, and means to enable said special universal bar to operate said carriage feeding mechanism, and means controlled by said type-actions and common to said pin-carrying bars, for setting them back to normal positions.
13. In a combined typewriting and computing machine comprising a typewriter carriage, a feeding mechanism therefor, numeral type-actions, a computing mechanism including rows of index pins or devices, denomination-selecting mechanism for said index pins or devices, bars or devices individual to said numeral type-actions for engaging the index pins or devices to set the same, means to enable said setting devices to operate the carriage feeding mechanism, and

- means to enable said setting devices to return the rows of index pins to normal positions.
14. In a combined typewriting and computing machine comprising a typewriter carriage, a feeding mechanism therefor, a universal bar mechanism to control said feeding mechanism, numeral type-actions having means connected to operate said universal bar mechanism, a computing mechanism including rows of index pins or devices, denomination-selecting mechanism controlled by said carriage for displacing index pins or devices, bars or devices individual to said numeral type-actions for setting the index pins or devices, and means to enable said setting devices to operate the typewriter universal bar mechanism and return the rows of index pins to normal positions.
15. In a combined typewriting and computing machine, the combination with a carriage, of numeral keys, numeral-key-actuated means to feed said carriage step by step, denominational members, a set of index devices on each of said denominational members, an index-device-setting means for each of said numeral keys, said denominational members being positioned normally with the index devices thereon out of range of the setting means, carriage-actuated means for bringing said denominational members seriatim into position to enable setting of index devices thereon, means individual to said denominational members tending to restore the same to their normal positions, and means actuated by any one of said setting means in setting the corresponding index device on a selected denominational member, for insuring the return to normal position of the next preceding denominational member, to prevent setting of an index device thereon.
16. In a combined typewriting and computing machine, the combination with a carriage, of numeral keys, numeral-key-actuated means to feed said carriage step by step, denominational members, a set of index devices on each of said denominational members, an index-device-setting means for each of said numeral keys, said denominational members being positioned normally with the index devices thereon out of range of the setting means, carriage-actuated means for bringing said denominational members seriatim into position to enable setting of index devices thereon, means individual to said denominational members tending to restore the same to their normal positions, and means actuated by any one of said setting means in setting the corresponding index device on a selected denominational member, for insuring movement of the selected denominational member to the proper position to enable setting of an index device thereon, and the return of the next preceding denominational member to normal position.
17. In a combined typewriting and computing machine, in combination, numeral keys, a carriage, carriage-escapement mechanism, denominational members having index devices thereon, carriage-actuated means to position said members to enable indexing thereon, numeral-key-operated setting devices universal to said denominational members, and means whereby said setting devices may actuate said escapement mechanism and concomitantly drive to normal position a denominational member previously advanced for indexing.
18. In a combined typewriting and computing machine, in combination, numeral keys, a carriage, carriage-escapement mechanism, denominational members having index devices thereon, carriage-actuated means to position said members to enable indexing thereon, numeral-key-operated setting devices universal to said denominational members, and means whereby said setting devices may actuate said escapement mechanism and concomitantly complete the movement to setting position of a selected denominational member and the return of the previously selected denominational member.
19. In a combined typewriting and computing machine, in combination, a typewriter carriage, feeding mechanism therefor, numeral type-actions, computing mechanism including denominational elements in which digits may be indexed, setting devices individual to said numeral type-actions for indexing digits in said denominational elements, denomination-selecting mechanism controlled by said carriage for displacing said elements to enable indexing to be effected therein, means to prevent interference by an operated setting device with the return of an indexed element and with the advance of the element of next lower denomination, and means whereby return of a previously-indexed element to normal position, before indexing in another element, may be effected by any one of said devices.
20. In a combined typewriting and computing machine, in combination, numeral keys, a carriage, denominational elements having sets of index devices settable in accordance with digits printed, carriage-actuated means to advance elements seriatim, to enable setting of said index devices, means urging each of said elements to normal position, key-operated devices for setting index devices on elements advanced by said carriage, and means operated by the keys for locking in advanced position the element advanced by the carriage, and the other elements in their normal positions.
21. In a combined typewriting and computing machine, in combination, numeral keys, a carriage, elements having rows of index devices, springs individual to said elements for returning the same to normal posi-

tions, key-operated index-pin setters, and key-controlled means to lock said elements either in normal positions or in index-device-setting positions during the operation of 5 said index-pin setters.

22. In a combined typewriting and computing machine, in combination, numeral-keys, a carriage, carriage-escapement mechanism, denominational members having indexing devices thereon, carriage-actuated means to position said members to enable indexing thereon, numeral-key-operated setting devices universal to said denominational members, and means controlled by 10 said setting devices to lock in position for indexing any of said members operatively positioned by the carriage.

23. In a combined typewriting and computing machine, in combination, a type-writer carriage, feeding means therefor, numeral type-actions, computing mechanism including denominational elements in which digits may be indexed, setting devices individual to and actuatable by said numeral type- 20 actions for indexing digits in said denominational elements, denomination-selecting mechanism controlled by said carriage for displacing said elements to enable indexing to be effected therein, and means rendered 30 effective by any one of said setting devices, when it is operated to index in a denominational element, to lock the other denominational elements in their normal positions.

24. In a combined typewriting and computing machine, in combination, a type-writer carriage, feeding means therefor, numeral type-actions, computing mechanism including denominational elements in which digits may be indexed, setting devices individual to and actuatable by said numeral type- 35 actions for indexing digits in said denominational elements, denomination-selecting mechanism controlled by said carriage for

displacing said elements to enable indexing to be effected therein, and means rendered 45 effective by any one of said setting devices, when the latter is operated to index in a denominational element, to lock the selected denominational element in effective position, and the others in their normal positions. 50

25. In a combined typewriting and computing machine, in combination, a type-writer carriage, feeding means therefor, numeral type-actions, computing mechanism including denominational elements in which 55 digits may be indexed, setting devices individual to said numeral type-actions for indexing digits in said denominational elements, denomination-selecting mechanism controlled by said carriage for displacing 60 said elements to enable indexing to be effected therein, and means whereby all of the unselected denominational elements will be locked in their normal positions while the digits are being indexed in the denominational 65 elements positioned to enable the setting devices to be effective thereon.

26. In a combined typewriting and computing machine, in combination, a carriage, denominational members having index devices thereon, denomination-selecting means to position said members to enable setting of index devices thereon, digital setting devices universal to said denominational members, and means whereby said setting devices, 70 during actuation thereof through the setting range of their movements, may prevent action of said denomination-selecting means and effect the proper positioning, and locking in proper position, of a denominational 75 member previously selected, and of the unselected denominational members.
